Primary Examiner—Cathron C Brooks*Assistant Examiner*—Austin Murphy*(74) Attorney, Agent, or Firm*—Steven E. Skolnick(57) **CLAIM**

The ornamental design for a small, portable power tool, as shown and described.

DESCRIPTION

FIG. 1 is a perspective view of a power tool showing the new design for a small, portable power tool;

FIG. 2 is a left side view thereof (the right side being a mirror image thereof);

FIG. 3 is a rear view thereof;

FIG. 4 is a front view thereof;

FIG. 5 is a bottom view thereof; and,

FIG. 6 is a top view thereof.

The broken lines shown in the drawings represent unclaimed portions of the Small, Portable Power Tool and form no part of the claimed design.
